UNITED STATES PATENT OFFICE

JOHANNES MICHAEL SCHMIERER, OF LICHTERFELDE, NEAR BERLIN, GERMANY, AS
SIGNOR TO RADIO PATENTS CORPORATION, OF NEW YORK, N. Y., A CORPORATION OF
NEW YORK

GLOW DISCHARGE AMPLIFIER

Original application filed December 24, 1924, Serial No. 757,854. Patent No. 1,720,352, dated July 9, 1929.
Divided and this application filed December 6, 1927, Serial No. 238,189, and in Germany January 23, 1924.

This application is a division of application U. S. Ser. 757,854, filed December 24, 1924, patented July 9, 1929, No. 1,720,352.

My invention relates to a new system of 5 amplification.

One object of my invention is to overcome the usual instability of the glow discharge tube so as to permit its use as an amplifier.

My invention provides a system of connection for amplifying alternating currents having no connection between the source of supply voltage and the source of current to be amplified and with only one connection between the voltage supply source and the 15 amplified circuit.

One embodiment comprises the use of a glow discharge tube having an anode and a cathode and two control electrodes. The anode and cathode are connected to the source 20 of supply and the current to be amplified is connected to the control electrodes. The tube is connected to a transformer of the receiving apparatus and through a potential divider that is connected across the supply 25 line.

My invention may be best understood by reference to the accompanying drawing.

In the figure a glow discharge device is indicated at B and as having an anode X, a 30 cathode K, and two control electrodes GX and GK. The anode X and cathode K are respectively connected to supply lines by means of conductors L1 and L2. The control electrodes are connected to the secondary 35 winding of transformer U. The primary winding of U has connected thereto any suitable source of alternating current that it is desired to amplify.

The control GK is connected to one side 40 of the primary winding of a transformer T that may be part of the receiving apparatus for the amplified current. The other side of the primary winding of the transformer 45 T is connected to the contactor S of a potential divider P that is connected in parallel with the anode and cathode supply line connections. The secondary winding of the transformer T may be connected to a telephone 50 or other receiving apparatus or a sec-

ond stage of amplification, etc., indicated generally at E.

This arrangement achieves amplification of electric current by a certain system of connections which can be explained as follows:—

The potential divider P is connected in parallel with a discharge tube B and the auxiliary electrode GK in this tube is connected electrically to the contactor S on the potential divider. The location of the contactor S is chosen in such a way that the voltage drop through the tube to the auxiliary electrode GK is exactly the same as the voltage drops in the branches Ww of the potential divider P. As a result, the connecting lead between the auxiliary electrode GK and the contactor S carries normally no current.

The second auxiliary electrode GX has a potential impressed upon it relatively to the first auxiliary electrode GK by means of the secondary of the transformer U. This potential will be of alternating nature corresponding to the voltage to be amplified. The result of the voltage impressed on the auxiliary electrode GX will be to modify the voltage distribution within the discharge tube B in such a way that there will be a difference of voltage established between electrode GK and contactor S on the potential divider. A current will result from the primary of the transformer T which is connected in this lead and the variation of voltage on the auxiliary electrode GX will therefore result in a corresponding variation of current in the primary of transformer T.

Modifications may be made within the spirit and scope of my invention and all such modifications are intended to be covered by the appended claims.

Having described my invention, what I believe to be new and desire to protect and secure by Letters Patent of the United States is:—

1. An amplifying circuit comprising a cold operating glow discharge tube, electrodes in said tube, power supply connected to said tube, means for conducting a potential to be amplified to said tube, a potentiometer connected across said power connections,

and a circuit from a point intermediate to said power connections of said potentiometer and said tube to carry the amplified control potential.

- 5 2. An amplifying circuit comprising a cold operating glow discharge tube, main and helping electrodes in said tube connections, for impressing a controlling potential on some of the electrodes in said tube, a circuit for receiving an amplified current from 10 said electrodes and a potentiometer connected in shunt with said main electrodes, said last named circuit being connected to a point of said potentiometer intermediate said 15 connections to main electrodes.
3. An amplifying device comprising a power line, a discharge tube having an anode and cathode connected to the line and having two auxiliary electrodes, a potential 20 divider connections therefrom to said power line, a connection from a point of the divider intermediate said power line connections to one of the auxiliary electrodes, a connection from one auxiliary electrode to 25 the other, means to apply to said last named connection a current to be amplified, to cause said second named connection to bear the amplified current.

4. An amplifying device comprising a 30 glow discharge tube, a pair of main and a pair of helping electrodes in said tubes, a circuit extending between said two helping electrodes, which circuit bears a current to be amplified, a potentiometer in shunt with 35 said electrodes and a connection extending from one of said helping electrodes of the tube to a point of the potentiometer intermediate said main terminals to receive said current after amplification.

40 5. An amplifying device comprising a discharge tube having an anode and cathode, a potential divider bearing at its ends the voltages of the anode and cathode, an auxiliary electrode in the tube connected to a point of 45 the potential divider of a voltage intermediate said anode and cathode voltages and means to cause a current to be modulated to flow between said auxiliary electrode and a second auxiliary electrode to cause said 50 current after amplification to flow between said first mentioned electrode and said intermediate point of the potential divider.

6. In an electric amplifier comprising a 55 gas discharge tube having a plurality of unheated electrodes, power connections across some of said electrodes to maintain a discharge within said tube, an amplification circuit connected to others of said electrodes, a potentiometer connected across the power 60 connections and means for tapping off a part of said power from the potentiometer for connection to one of said last mentioned electrodes.

7. In a gas discharge tube, a first unheated 65 electrode, a second electrode, means for ap-

plying a potential between said electrodes, a third electrode, a connection from said third electrode to said last mentioned means, the connection being balanced with respect to the potential so no current normally flows there- 70 in, a fourth electrode, means for varying potential of said fourth electrode, and circuit connections whereby said potential variations of the fourth electrode produces corresponding current flow in said first mentioned 75 connection.

8. In a gas discharge tube, a first and second electrode, means for applying a potential between said electrodes, a third electrode, a receiver circuit connected to said third electrode, there being normally no potential difference between both sides of the receiver, a fourth electrode, means for varying the potential of said fourth electrode, circuit connections from said fourth electrode to said 80 third electrode whereby variations of potentials of said fourth electrode varies the potential of said third electrode whereby the potentials on one side of said receiver is changed with respect to the other side to produce a 85 current flow therebetween.

9. In a gas discharge tube, a first and second electrode, means for maintaining a potential between said electrodes, a third electrode interposed between said first and second electrode, circuit connections from said third electrode to said first mentioned means so arranged that the potentials between said first and third electrodes equals the potential of said means between said first electrode and 95 said circuit connections to said means whereby the potential between said third electrode and said circuit connection normally is zero, a fourth electrode, means for varying the potentials thereof and means controlled by said 100 fourth electrode for varying the potentials of said third electrode with respect to said circuit connection at said means.

10. In a cold glow discharge tube, first and second unheated electrodes, a single source of 110 power for operating said tube, said source of power being connected between said electrodes, a third electrode, a potentiometer connection from said third electrode to said source of power such as to normally maintain 115 a balanced condition with respect to said source, a fourth electrode, means for varying the potentials of said fourth electrode and means whereby varying potentials of said 120 fourth electrode vary the potentials of said third electrode for unbalancing said electrode with respect to said source.

11. In a cold gas discharge tube, a first cold electrode, a second electrode, a source of current to be amplified, said source of current 125 being connected to said second electrode, a main source of power, a circuit connecting said first and second electrodes to said source of power, a receiver connected to said circuit, a third electrode connected to said source 130

whereby there is normally no potential difference from said second electrode and said source of power through said receiver and a fourth electrode controlled by said source of current for varying the potential of said electrode with respect to said source of power.

12. In combination a gas discharge tube with a plurality of electrodes, a Wheatstone bridge connection between three of the electrodes of said tube to form the two arms of said bridge, a potentiometer to form the two corresponding arms of the bridge, an output circuit connected in the diametrical connection of the bridge, and a power supply connected to the other diametrical connection to impress its potential upon said tube, means for unbalancing the arms comprising the tube, said means including an input circuit whereby the current in said input circuit produces an amplified image current in said output circuit.

13. In a gas discharge tube, a plurality of cold electrodes, a source of current to be amplified, said source of current being connected to one of said electrodes, a main source of power, current connections from said electrodes to said source of power for maintaining said electrodes at predetermined potentials, a receiver connected to one of said electrodes through said circuit connections, there being normally no potential difference from said receiver connected electrode to the source of power tap of said same electrodes, and means controlled by said source of current for varying the potential of said last named electrode with respect to said source of power tap thereof.

14. In an electric amplifier comprising a gas discharge tube having a plurality of unheated electrodes, power connections across some of said electrodes to maintain a discharge within said tube, an amplification circuit including two of said electrodes, a potentiometer connected across said power connections, and means for tapping off from said potentiometer for connection to said electrodes.

In testimony whereof I have affixed my signature.

JOHANNES MICHAEL SCHMIERER.
